COMBUSTION CONTROLLING DEVICE FOR
FURNACES

Bradford G. Woolley, Providence, R. I., assignor
to Hammel Oil Burning Equipment Company,
Inc., Providence, R. I., a corporation of Rhode
Island

Application January 12, 1934, Serial No. 706,382

17 Claims. (Cl. 158—1)

This invention relates to an improved control device for regulating combustion in furnaces. The invention is directed particularly to a combustion-controlling device for steam boilers using fuel-oil atomized by steam or air to produce combustion.

One object of the invention is to provide a device of the type indicated which may be operated from a single control to regulate the feed 10 of oil and steam or air to the burner in correct proportion to obtain maximum efficiency of operation and freedom from dangerous conditions liable to result from overloading.

Another object of the invention is to provide a 15 device of the type indicated which is adjustable to meet varying requirements when used in conjunction with furnaces of different types and capacities.

Another object of the invention is to provide a 20 device of the type indicated which may be operated directly from the draft-controlling means of the furnace to insure proper coöperation therewith.

Another object of the invention is to provide a 25 device of the type indicated which is embodied in a single unit adapted for application to furnaces already in use without material change in their structure.

Another object of the invention is to provide a 30 device of the type indicated which is of simple and rugged construction to adapt it for use over long periods of time without repair or replacement.

Further objects of the improvement are set 35 forth in the following specification which describes a preferred form of construction of the invention, by way of example, as illustrated by the accompanying drawings. In the drawings:

Fig. 1 is a front elevation of a steam boiler furnace of industrial type showing the improved control device as applied to use therewith and connected to be operated from the draft-regulating means;

Fig. 2 is a side elevation of the same;

Fig. 3 is an enlarged front view of the control device showing the relationship of the parts when adjusted to reduce the feed of oil and steam to a minimum;

Fig. 4 is a sectional plan view of the control device taken on line 4—4 of Fig. 3;

Fig. 5 is a side view of the control device showing the feed-valves adjusted to substantially closed position;

Fig. 6 is a similar view showing the valves in

full open position to effect maximum flow of oil and steam to the burner;

Fig. 7 is a combination end and sectional view of the steam-valve taken on line 7—7 of Fig. 3 with the valve-plug shown in substantially closed 5 position;

Fig. 8 is a combination end and sectional view through the oil-valve taken on line 8—8 of Fig. 3 and showing the valve-plug in substantially closed position; 10

Fig. 9 is a view similar to Fig. 7 showing the steam-valve opened to effect maximum flow of steam to the burner;

Fig. 10 is a view similar to Fig. 8 illustrating the oil-valve fully opened to permit maximum 15 flow of oil to the burner; and

Fig. 11 is a perspective view of the valve-plug used in the oil-valve.

The present improved control device comprises, in general, a plate or panel adapted to be secured 20 to the front of the furnace or boiler and provided with a pair of valves, one for controlling the supply of oil to the burner and the other for regulating the feed of steam or air thereto for atomizing the fuel. The valve-panel is generally located at 25 a point remote from the burner with feed-pipes leading from the control-valves. Means are provided for operating the valves in synchronism to regulate the supply of fuel and steam in correct proportion to obtain proper burning of the 30 fuel in the furnace. In this manner combustion may be positively controlled and accurately regulated to meet the various firing conditions and steam demands. In the following description the term "steam" is used in a generic sense as indicating any suitable atomizing agent whether of 35 a liquid or gaseous nature.

Referring first to Figs. 1 and 2 of the drawings, the steam boiler herein illustrated is of a conventional industrial type enclosed by masonry 2 40 and a front plate 3. The front plate 3 is provided with the usual fire-box and ash-pit doors designated 4 and 5, respectively. The ash-pit doors 5 are pivotally mounted on hinge-rods 6 to adapt them to be swung into open or closed 45 position to control the primary draft to the furnace. Extending horizontally at the front of the boiler is a control-shaft 8 journaled in bearings 9 on the plate 3. The shaft 8 carries levers 10 connected to the ash-pit doors or dampers 5 by chains 11, one end of each chain being attached to a lever 10 and its opposite end connected to an arm 12 extending laterally from the door 5. The control-shaft 8 may be manually turned by means of a handle 15 fixed to one end thereof or 55

automatically operated from a suitable motor. The handle 15 is provided with a stud 16 passing through an arcuate slot 17 in a quadrant 18, see Fig. 2, fastened to the side of one of the bearings 9. A hand-nut 19 on the stud 17 may be tightened against the quadrant 18 to retain the handle 15 in adjusted position.

At the top of the boiler is a flue 20 in which is rotatably mounted a shaft 21 carrying a butterfly valve or damper 22 adapted to be operated from the control-handle 15. At one end of the damper-shaft 21 is a semi-circular member 23 to which is attached a chain 24 connected at its opposite end to an arm 25 fast on the control-shaft 8. The damper 22 is controlled by means of a spring or weight of usual type to cause it to open when the handle 15 is swung upwardly from the position illustrated in Fig. 2. In addition to operating the dampers in the manner as above explained the handle 15 may also serve to operate the feed-control device for the burner by means as later described.

The boiler may be provided with any suitable type of oil-burner nozzle, indicated at 27 in Fig. 1 as projecting into the fire-box of the furnace. Connected to the outer end of the nozzle 27 are two feed lines 28 and 29 leading from the control device, the pipe 28 being for oil and pipe 29 for steam or air. A double indicator 30 at the front of the boiler is connected by tubes 31 and 32 to the oil and steam feed-pipes 28 and 29 to register the pressure in each. The control device for regulating the supply of oil and steam to the burner is constructed and arranged as next described.

Secured to the front plate 3 of the boiler by means of bolts 34 is a small plate or panel 33. The bolts 34 pass through the corners of the panel 33 and through tubes 35 which space the panel outwardly from the front plate 3 to insulate it from heat and also to provide room for the oil and steam supply-pipes 36 and 37 which are connected to the rear of the panel. As shown in Figs. 4 and 5 the panel 33 is provided with circular bosses 38 and 39 having threaded bores extending through the panel. Screwed into the rearward ends of the bosses 38 and 39 are the supply-pipes 36 and 37 for oil and steam; the oil feed line 36 leading from a suitable source of supply and the steam pipe 37 from the boiler. Shut-off valves 13 and 14 are provided in the lines 36 and 37 for manually shutting off the feed. Connected to the forward ends of the bosses 38 and 39 by nipples 41 are oil and steam control-valves 40 and 50. As both valves are similar in construction only one will be herein described in detail.

Referring to Fig. 4, the valve 40 comprises a body 42 in the shape of a cross having two branches disposed in right angular relationship. Communicating with the supply-pipe 36 through the nipple 41 is an inlet passage 43 and opposite thereto is an outflow passage leading to the feed-pipe 28 which connects with the burner-nozzle 27. The flow of the oil through the passage 43 is regulated by a valve-stem 44 extending transversely thereof.

The valve-stem 44, shown in detail in Fig. 11, comprises a cylindrical body-portion with a reduced shank 46 projecting axially therefrom. Extending diametrically through the body-portion of the stem 44 is a port 47 of substantially triangular shape in cross-section, see Fig. 10, adapted to register with the inlet 43 when the

stem is turned in the valve-body 42. As shown in Fig. 4, the shank portion of the valve-stem 44 is fitted to a bore 48 in the valve-body 42 and its enlarged portion seats in a counterbore 49 extending from the opposite side thereof.

The inner end of the counterbore 49 is tapered slightly to form a seat 51 for receiving the enlarged portion of the valve-stem 44 which is correspondingly tapered as shown at 52. Screwed into an enlarged threaded counterbore 55 in the end of the valve-casing 42 is a plug 56. Packed in an axial hole 57 in the plug is a spring 58 which bears against the end of the enlarged portion of the valve-stem 44 to maintain its opposite tapered end 52 firmly seated in the tapered end 51 of the counterbore 49 to form a seal for preventing leakage. As a further prevention against leakage around the valve-stem a stuffing box is provided. The valve-body is formed with a projecting gland 59 enclosing a suitable packing 60 compressed in the gland by a sleeve 61 held by an adjusting nut 62 screwed onto the threaded end of the gland.

Referring now to Figs. 3 and 7 to 10 inclusive, the triangular openings or ports 47 in the steam and oil valve-stems are oppositely disposed. That is to say, the apexes of the triangular holes point in opposite directions so that when the valve-stems are turned in opposite directions the two valves 40 and 50 are concurrently opened or concurrently closed. The means for turning the valve-stems to open and close the valves are constructed and arranged as next described.

Extending lengthwise of the panel 33 at right-angles to the valve-stems 44 is a projecting rib 35 or pad 65 provided with a substantially T-shaped slot or guideway 66. Slidably mounted in the guideway 66 is a bar 67 connected to operate the valves 40 and 50 either from the control-shaft 8 or a handwheel 80 to be later described. Communicating with the guideway 66 is a narrower slot 68 for receiving a gear-rack 70 fastened to the rearward side of the bar 67 by means of screws 71, see Figs. 4 and 6.

As shown in Fig. 6 a pinion 72 meshes with the gear-rack 70 and by turning the pinion the rack and its attached slide-bar 67 may be moved longitudinally of the panel 33. The pinion 72 is carried on or formed integral with a shaft or spindle 73 rotatably mounted in a bore 74 in the panel 33 which extends at right-angles to the guideway 66 at the rear thereof. The pinion 72 is slightly larger in diameter than the spindle 73 and a bushing 75 in the bore 74 engages its inner end to retain the spindle in place in the bore. The bushing 75 constitutes a bearing for the spindle 73, being held in place in the bore 74 by means of a set-screw 76. A collar 77 secured to the spindle 73 by a set-screw 78 abuts the side of the panel 33 to take the thrust of the spindle 73 in the opposite direction. Secured to the projecting end of the shaft 73 is a handwheel 80, previously referred to, which serves as the means for rotating the pinion 72 to slide the bar 67 in its guideway 66. The handwheel 80 is employed for manually adjusting the feed-valves independently of the draft-regulating handle 15, previously described. When the control-handle 15 is manipulated to regulate the draft in the furnace the bar 67 is simultaneously actuated to open or close the valves 40 and 50. Connected to the upper end of the bar 67 is a link 81, see Figs. 1 and 2, which is pivotally joined to a lever 83 on the control-shaft 8.

5 Detachably secured to the slide-bar 67 are two valve-operating cams 84 and 85. Referring to Figs. 3, 5 and 6, the cams 84 and 85 are constituted by relatively thin bars or bendable strips shaped to extend at predetermined angles in relation to the bar 67. At their outer ends the cam-strips 84 and 85 are slotted to receive studs or screws 86 inserted through the ends of the slide-bar 67. As herein shown the heads of the 10 screws 86 fit within countersunk holes in the rearward side of the bar 67 with the threaded ends of the screws projecting forwardly to receive nuts 87 screwed against the bar. The slotted ends of the cam-strips 84 and 85 are detachably fastened against the nuts 87 by means of binder-nuts 88 screwed down thereagainst. The opposite overlapping ends of the cam-strips 84 and 85 are secured to a longer stud 89 projecting forwardly from the slide-bar 67 to extend through 15 their slots. The stud 89 is screwed into a threaded hole in the slide-bar 67 and on its outer threaded end are nuts 90, 91 and 92, between which the ends of the cam-strips 84 and 85 are clamped. It will be observed by reference to Figs. 20 5 and 6 that the inner ends of the cams 84 and 85 are disposed at different distances from the slide-bar 67; the steam-valve control cam 85 being of slightly greater inclination or pitch than the cam 84 which controls the opening and closing 25 of the oil-valve 40.

40 Secured to the outer extremities of the valve-stems 44 are arms or levers 95 and 96. The arms 95 and 96 have split hubs 97 clamped to the stems 44 by binder-screws 98. Each arm 95 or 96 is formed at its end with a yoke 99 between the sides of which is a roller 100 journaled on a pin 101. The rollers 100 are adapted to ride up and down the incline of the cams 84 and 85 to turn the valve-stems when the slide-bar 67 is moved 45 in either direction.

45 The arms or levers 95 and 96 are maintained with their rollers 100 in engagement with the cams 84 and 85 under the action of spring-controlled plunger-rods 105. Referring to Fig. 4 of the drawings the plunger-rods 105 slide through holes 106 in the panel 33, being provided with helical springs 116 enclosing their projecting ends and held under compression by washers 115 and nuts 117. The rods 105 are connected to the 50 arms or levers 95 and 96 by articulated joints embodied in heads 107 at the ends of the rods. One side of each head 107 is slotted to receive the spherical end 110 of a stud 109 screwed into the side of the arm 95 or 96, as the case may be. The spherical head 110 of the stud fits within a bore 108 in the head or socketed end 107 of the 55 rod 105. A plunger 111 formed with a concaved recess is slidably held within the bore 108 and pressed against the head 110 of the stud 109 by means of a helical spring 112 pocketed in the bore. The bore 108 is threaded to receive a plug 113 screwed thereinto to take the thrust of the head 110 under the pressure of the spring-plunger 111.

60 Through the above described ball-and-socket joints the plunger-rods 105 are connected to the arms or levers 95 and 96 to maintain their rollers 100 continuously in engagement with the cams 84 and 85. The upward sliding movement of the bar 67 causes the arm 95 to be turned in clockwise direction by the cam 84 and the arm 96 to be rocked in the opposite direction by the cam 85; while movement of the bar in the opposite direction effects a reverse rocking motion 65 of each of the arms. The arrangement of the

control device having now been described in detail its method of operation will next be explained.

70 Assuming that the feed-controlling or regulating device is connected to be operated from the control-shaft 8 and that the control-handle 15 is in lowermost position as shown in Figs. 1 and 2, the valve-stems 44 of the feed-valves will be in a substantially closed position. That is to say, with the slide-bar 67 in lowermost position as illustrated in Fig. 5 the valve-arm 96 will be held depressed under the action of its plunger-rod 105 while the arm 95 is rocked outwardly away from the panel 33. To start combustion in the fire-box of the boiler the valves 13 and 14 75 15 in the oil and steam supply-lines 36 and 37 are first opened to cause the oil and steam to be supplied under pressure to the control device. Referring to Figs. 7 and 8 of the drawings, it is noted that the oil and steam feed-valves 40 and 20 50 25 30 35 40 45 50 55 60 65 70 75 80 85 90 95 100 105 110 115 120 125 130 135 140 145 150 155 160 - operator simply depresses the control-handle 15 to partly close the dampers 5 and 22 and simultaneously lower the slide-bar 67. As the bar 67 is slid downwardly, for example to lowest position as shown in Figs. 3 and 5, the cam 84 rocks the arm 95 to turn the valve-stem 44 in counter-clockwise direction to partially close the port 47 of the oil-valve 40 as indicated in Fig. 8. Concurrently therewith the arm 96 will be rocked 10 to turn the valve-stem 44 in the steam-valve 50 in clockwise direction to partially close its port 47 as shown in Fig. 7. It will be understood that the valves 40 and 50 and the dampers 5 and 22 may be accurately adjusted to a mean operating 15 position as determined by the steam pressure necessary to supply the demand. This is accomplished by turning the handle 15 to different positions between the extremes of movement above described.
- 20 It has been explained that in the present embodiment of the invention the pitch or angle of inclination of the steam-controlling cam 85 is greater than that of the oil-regulating cam 84. This provides that the steam-valve 50 will be opened and closed more quickly than the oil-valve 40. This condition is desirable in the operation of certain types of steam boilers and for meeting their particular requirements. The proportionate rates of movement of the valve-stems 44, may, however, be varied to meet other requirements when the control device is applied to use with steam boilers of different capacities, such adjustment being made when installing the device. Cam-strips 84 and 85 of various shapes 30 may be supplied and assembled on the bar 67 as needed or, in other instances, the strips may be bent to the required contour to effect the desired inclination before application of the device to the boiler.
- 35 The control unit may be arranged to be operated automatically by a suitable motor, either electric or hydraulic, controlled by the developed steam-pressure to regulate the dampers and feed-valves to maintain a predetermined pressure in the boiler.
- 40 The present improved device is adaptable for general use in controlling combustion in furnaces supplied with liquid fuel and atomized by means of steam or air. In other instances it may be applied to use for adjusting a single feed-valve by dispensing with one of the cams. It may also be used in conjunction with feed-valves employed for other purposes in various arts.
- 45 The device is positive in operation and when once adjusted to meet the predetermined conditions it requires practically no attention on the part of the operator. When the device is operated from the draft-controlling means the control-shaft 3 may be extended along the front of a battery of boilers and the combustion in the several boilers simultaneously regulated from a single panel with feed-pipes leading to each of the burners.
- 50 The improved device synchronizes the control 55 of the supply of oil and steam to the burner or burners to accurately limit the feed of the fuel and steam or air to the minimum required for any load. The oil and steam valves are positively opened and closed by the interlocked cams, thus giving each valve its own degree of opening. The cams may be readily adjusted to compensate for wear or change in operation conditions.
- 55 With the use of the present improved device the hazardous condition resulting from overloading is entirely eliminated since the rate of feed of

the fuel to the burner is positively controlled at all times and it is impossible to increase the flow of the oil without simultaneously increasing the flow of the atomizing agent. The device thus makes for greater efficiency in operation and results in a substantial saving of fuel by eliminating waste. 5

While I have herein shown and described the improved combustion-controlling device as embodied in a preferred form of construction and applied to use with a particuar type of boiler, it is to be understood that various modifications may be made in the structure of the device and its application to use without departing from the spirit or scope of the invention. Therefore, without limiting myself in this respect, I claim:

1. In combination with a furnace, a burner therefor, a conduit for feeding fuel to the burner, a valve in said conduit for controlling the feed, a second conduit for feeding air or steam to atomize the fuel supplied to the burner, a valve in said second conduit for controlling the last-named feed, cams for operating said valves in synchronism, and a slide having a straight line motion for actuating the cams in unison. 20

2. In combination with a furnace, a burner therefor, a conduit for feeding fuel to the burner, a valve in the conduit for controliing the feed, a second conduit for feeding air or steam to atomize the fuel supplied to the burner, a valve in the second conduit for controlling the flow of the medium therein, cams for operating said valves in synchronism, a slide for actuating the cams in unison, dampers for controlling the draft in the furnace, means for operating said dampers, and means connecting said damper-operating means and slide to move the latter to actuate the cams for the valves. 25

3. In a control device for furnaces, the combination of a pair of conduits, one for fuel and another for air or steam, valves for regulating the flow of fluid through each conduit, a plurality of cams for operating the valves, means for actuating the cams to open and close the valves in unison, and means for independently adjusting 40 the cams at one end to regulate the ratio of adjustment of the valves during their synchronous operation from the cams. 45

4. In a control device for furnaces, the combination of a pair of conduits, one for fuel and another for air or steam, valves for regulating the feed through each conduit, a panel, a slide 50 slidable on the panel, cams mounted on said slide and engageable with the valves to actuate the latter in unison, and means to slide the slide on 55 the panel.

5. In a control device for furnaces, the combination of a pair of conduits, one for fuel and another for air or steam, valves for regulating the feed through each conduit, a panel, a slide 60 slidable on the panel, a rack on the slide, a pinion engaging the rack to slide the slide, means for turning the pinion, and cams on the slide engageable with the valves to actuate the latter during the movement of the slide. 65

6. In a control device for furnaces, the combination of a pair of valves, one for fuel and another for air or steam, a lever for controlling each valve, a slide, cams mounted on the slide and adjustable in angular relation thereto, means 70 on the levers engaging the cams, rods attached to the levers, and springs acting on said rods to maintain the levers in engagement with the cams during the movement of the slide.

7. In a control device for furnaces, the com- 75

bination of separate conduits for feeding fuel and an atomizing medium, a valve in each conduit for regulating the flow of the medium therein, actuators for the valves, a reciprocable slide adjacent the actuators, inclined cams on said slide engaged by the respective valve-actuators to open or close the valves upon movement of the slide, and means for adjusting the cams at one end to vary the inclination thereof throughout their length.

8. In a control device for furnaces, the combination of separate conduits for feeding fuel and an atomizing medium, a valve in each conduit for regulating the flow of the medium therein, actuators for the valves, a reciprocable slide adjacent the actuators, flexible strips on said slide inclined with respect to its direction of movement and engaging the valve-actuators, and adjusting means at the end of the strips for varying the inclination of said strips.

9. In a control device for furnaces, the combination of separate conduits for feeding fuel and an atomizing medium, a valve in each conduit for regulating the flow of the medium therein, actuators for the valves, a reciprocable slide adjacent the actuators, cams mounted on said slide in inclined position with respect to the direction of movement thereof, resilient means for holding the valve-actuators in engagement with the cams, and means at the end of the cams for adjusting the inclination thereof whereby said valves are variably actuated by movement of the slide to regulate the proportions of fuel and air supplied to the furnace.

10. In a control device for furnaces, the combination of separate conduits for feeding fuel and an atomizing medium, a valve in each conduit for regulating the flow of the medium therein, said valves being operable in opposite directions to open or close the conduits, actuators for the valves, and movable cams inclined in opposite directions and engaged by the respective valve-actuators whereby the valves are operated in opposite directions to simultaneously open the conduits when the cams are moved in one direction and simultaneously close the conduits when the cams are moved in the opposite direction.

11. In a control device for furnaces, the combination of separate conduits for feeding fuel and an atomizing medium, a valve in each conduit for regulating the flow of the medium therein, said valves being operable in opposite directions to open or close the conduits, actuators for the valves, a slide adjacent the actuators, cams on the slide having oppositely inclined faces engaged by the actuators, and means for adjusting the inclination of the cams, said valves being actuated in opposite directions by movement of the slide to simultaneously open or close the conduits.

12. In a control device for furnaces, the combination of separate conduits for feeding fuel and an atomizing medium, a valve in each conduit for regulating the flow of the medium therein, said valves being operable in opposite directions to open or close the conduits, actuators for the valves, a slide adjacent the actuators, cams on said slide having faces inclined in opposite directions to a common peak, and means at one end of the cams

for adjusting their inclination throughout their length, said cams engaging the respective valve-actuators to simultaneously open or close the valves upon movement of the slide in opposite directions.

13. In a control device for furnaces, the combination of separate conduits for feeding fuel and an atomizing medium, a valve in each conduit for regulating the flow of the medium therein, said valves being operable in opposite directions to open or close the conduits, actuators for the valves, a slide adjacent the actuators, oppositely inclined cams on said slide, and resilient means for holding the valve-actuators in engagement with the respective cams whereby the valves are operated in opposite directions to simultaneously open or close the conduits upon movement of the slide.

14. In a control for furnaces, the combination of separate conduits for feeding fuel and an atomizing medium, a valve in each conduit for regulating the flow of the medium therein, said valves being operable in opposite directions to open or close the conduits, levers for actuating the valves to open or close the conduits, a slide adjacent the levers, oppositely inclined cams on the slide, and resilient means for holding the levers in contact with the respective cams, said valves being operated in opposite directions upon movement of the slide in either direction by the engagement of the actuating levers with the cams.

15. In a control device for furnaces, a panel, separate conduits extending through the panel for feeding fuel and an atomizing medium, a valve in each conduit for regulating the flow of the medium therein, actuators for said valves adjacent said panel, a slide on said panel having cam faces for engaging the respective valve-actuators, and manually-operable means for reciprocating the slide on the panel to simultaneously actuate the valves.

16. In a control device for furnaces, a panel, separate conduits extending through the panel for feeding fuel and an atomizing medium, a valve in each conduit for regulating the flow of the medium therein, actuators for said valves adjacent said panel, a slide on said panel having cam faces for engaging the respective valve-actuators, a damper for the furnace, means for connecting the damper with the slide, and manually-operable means for reciprocating the slide to simultaneously actuate the valves and the damper.

17. In a control device for furnaces, a panel, separate conduits extending through the panel for feeding fuel and an atomizing medium, a valve in each conduit for regulating the flow of the medium therein, said valves being operable in opposite directions to open or close the conduits, actuators for said valves adjacent said panel, a slide on said panel, cams on said slide having oppositely inclined faces engaged by the respective valve-actuators, a damper for the furnace, means for connecting the damper with the slide, and manually-operable means for reciprocating the slide to simultaneously actuate the damper and the valves in opposite directions.

BRADFORD G. WOOLLEY.
